LIFESAVING DEVICE FOR SUBMARINES

James E. Clanton, Portsmouth, Va.

Application August 26, 1937, Serial No. 161,126

1 Claim. (Cl. 114—16.6)

The invention relates to a life saving device for submarines and more especially to a safety escape attachment for submarines or the like.

The primary object of the invention is the provision of a device of this character, wherein the crew of men within a submarine when the latter becomes disabled after sinking within a body of water can be readily let out from the said submarine without liability of the flooding of the latter and in this way the crew can become freed and at the same time leaves the submarine watertight thus the submarine, after the men have left the same, may be brought to the surface of the water without being flooded and the exact cause of disablement may be determined easily and necessary repairs made.

Another object of the invention is the provision of a device of this character, wherein the construction thereof is novel in its entirety and is automatic in the working thereof so that a trapped crew within a submarine can be readily freed or make escape therefrom particularly when the vessel is beneath the water level or not afloat.

A further object of the invention is the provision of a device of this character, which is simple in construction, thoroughly reliable and effective in operation, assuring safety to a prisoned crew of a submarine, automatically operative, durable, and inexpensive to manufacture and install.

With these and other objects in view, the invention consists in the features of construction, combination and arrangement of parts as will be hereinafter more fully described, illustrated in the accompanying drawings, which disclose the preferred and modified forms of embodiment of the invention and pointed out in the claim hereunto appended.

In the accompanying drawings:

Figure 1 is a side elevation of a submarine showing the device constructed in accordance with the invention and applied.

Figure 2 is a fragmentary top plan view thereof.

Figure 3 is a vertical transverse sectional view showing the device in normal closed position.

Figure 4 is a view similar to Figure 3 showing the device open for the escape of a crew from a submarine.

Figure 5 is a fragmentary top plan view showing in detail the driving connections between a motor and adjuncts thereof.

Figure 6 is a fragmentary vertical sectional view through the device showing a slight modification.

Similar reference characters indicate corre-

sponding parts throughout the several views in the drawings.

Referring to the drawings in detail, A designates generally a submarine being equipped as such and rising from the hull 10 thereof fore of the same is a columnar vertically disposed body 11 forming a hatch way and open at its top while hinged exteriorly to this body 11 is an upwardly arched cover or closure 12, the hinge being indicated at 13, so that said closure will swing vertically in the opening and closing movements thereof. Leading from the interior of the hull 10 to a hatch opening 14 therein which establishes communication between the hull and the said body 11 is a ladder 15, the opening 14 being closed by a vertically swinging hatch door 16 adapted to be manually raised and lowered for the opening and closing movements thereof. Access may be had to the interior of the hull 10 or an exit therefrom through the opening 14 on the opening of the hatch door 16 in that the crew can enter through the hatch way effected by the body 11 or make an exit therefrom through the open top of said body 11.

Rotatably supported within the hull 10 is a windlass 17 which through gearing connections 18 is operated by an electric motor 19 and this motor is included in an electric circuit 20 which also has arranged therein a storage battery 21, the latter being confined within the hull. Located within the body 11 is an electric light 22 which is included in a circuit 23 between it and the battery 21 while arranged in this circuit 23 and located in the body 11 is a hand switch 24 so that the light can be turned on and off at will within said body 11.

Properly arranged exteriorly of the hull 10 close to the body 11 is a standard 25 having at its upper end a pulley wheel 26 for a raising and lowering chain 27, it being connected to the closure 12 and is adapted for winding and unwinding on and from the windlass 17, being connected thereto in any suitable manner. This chain has interposed therein a straight guiding section 28 which operates through a suitable packing gland built with the hull 10 of the submarine A.

In the circuit 20 are the swinging arms 29 and 30, respectively, of an opening and closing switch, the arm 30 being operated from a depressible pedal 31 while the arm 29 is operated by a connecting chain 32 with the chain 27. The arm 29 of the switch is normally held in a substantially horizontal position by a spring 33 and in this position the arm 30 of the said switch is suffi-

ciently elevated for the holding of the switch in open position. The arms 29 and 30 of the switch, which is of the double acting type, cooperate with an interposed stationary contact. Now when the closure 12 is in closed position and an operator within the body 11 depresses the pedal 31, the arm 30 is caused to make contact with the arm 29 and thus close the circuit 20 to the motor 19, the circuit being normally open. On the closing of the said circuit, the motor 19 is started operating the windlass 17 and through the chain 27 the closure 12 is opened. When the chain 27 has been wound sufficiently on the windlass 17 to pull upon the chain 32, the switch arm 29 will be shifted out of contact with the arm 30 and thus this switch in the circuit 20 opened and similarly opening the said circuit which stops the motor.

The trap door 16 is equipped with a sealing gasket 34 and similarly the body 11 is equipped with a sealing gasket 35 so that when the closure 12 is in closing position a water-tight joint is assured to avoid any possibility of leakage of water into the columnar body 11. Similarly when the door 16 is closed any water contained within the body 11 can not gain entrance to the hull 10 of the submarine.

When the submarine is submerged in a body of water and becomes disabled, being necessary that the crew make an escape therefrom, the said crew leaves the hull 10 by way of the ladder 15 and enters the body 11, the hatch door 16 being for this purpose. On entering the body 11 the hatch door 16 is closed sealing the opening 14 and the light 22 is turned on by closing the switch 24, it being understood, of course, that the closure 12 is in closed position. Now an operator depresses the pedal 31 closing the switch including the arms 29 and 30 and the motor 19 starts causing the winding of the chain 27 on the windlass 17 thus opening the closure 12 so that the crew within the body 11 can make an exit through the open top thereof.

In Figure 6 of the drawings there is shown a slight modification, wherein the closure 36, which is similar to the closure 12, has associated therewith a wire net apron 37 which forms a water guard on initial opening of the closure 36 to avoid injury to the occupants of the body 11 through inrush of water at the moment of the opening of the closure 36 and in this manner the said apron 37 is a protector against the force of the water at the time of initially opening the closure.

The instant that the closure 12 is opened, the switch having the arms 29 and 30 is opened automatically and in this manner the motor 19 is stopped.

The closure 12 when in closing position is suitably bolted as at 38 to secure the same in its closing position, these bolts being readily removed when it is desired that the closure 12 be opened.

What is claimed is:

A life saving device for a submarine having a hull provided with a closable top hole, comprising a columnar body rising vertically from said hull for forming a hatch way to said hole, a hinged cover to said columnar body for opening and closing movements, a power unit interiorly of the hull, an electric switch having operating means accessible within the hatch way, an electric circuit having the power unit and switch arranged therein, a packing gland built with the hull at the top thereof, a movable counterweight element slidably fitting the gland for extension without and within the hull, flexible connections between the power unit and the cover, respectively, and a guide fixed exteriorly of the hull at the top thereof and extended upwardly beyond the path of swing of the said cover and having the flexible connection between said element and said cover movable thereover.

JAMES E. CLANTON. 40
